UNITED STATES PATENT OFFICE.

JAMES R. MOFFATT AND RALPH S. KELSO, OF CHICAGO, ILLINOIS, ASSIGNORS TO UNION SPECIAL MACHINE COMPANY, OF CHICAGO, ILLINOIS, A CORPORATION OF ILLINOIS.

SEWING-MACHINE.

1,209,009.

Specification of Letters Patent. Patented Dec. 19, 1916.

Application filed January 4, 1912. Serial No. 669,397.

To all whom it may concern:

Be it known that we, JAMES R. MOFFATT and RALPH S. KELSO, citizens of the United States, residing at Chicago, in the county 5 of Cook, State of Illinois, have invented certain new and useful Improvements in Sewing-Machines, of which the following is a description, reference being had to the accompanying drawing and to the letters and 10 figures of reference marked thereon.

Our invention relates to improvements in sewing machines and particularly to a movable folder or edge turner for turning the edge of the fabric before sewing, with 15 means for rendering the turner effective or ineffective at the will of the operator, and that too, without interfering with the action of the stitch forming mechanism.

In an application heretofore filed by Henry 20 J. Dahl on the 6th day of October 1910, Serial No. 585,611, the throat plate of a Union Special overseaming machine, such as illustrated in Patent No. 962,974, of June 28th, 1910, is shown as provided with a stationary edge turner located between the 25 trimmer and the stitch forming mechanism for turning a slight fold on the edge of the fabric to be overseamed, the folded edge being covered and stitched down (and if desired, 30 a tape secured thereto also) by the overseam stitches. We have found it desirable to provide an edge turner which at the will of the operator may be manipulated to be effective or ineffective so that on different 35 classes of goods, or on different portions of the same work, the edge may be turned and overseamed, or left unturned or flat and overseamed, as desired. For example, in the manufacture of pockets and 40 securing them to garments, in the hanging or unattached part of the pocket, and where the strain comes, the edge turner is used to fold over the edge making a strong binding or seam, but when sewed to the body of the goods, a flat seam is desired, thus a movable 45 edge turner is used which may be thrown into and out of operation while the sewing is progressing.

While the invention is of especial value in 50 connection with overseaming machines, where the edge is bound by the overseaming stitches, and where too, a development of the

invention which consists in utilizing the turner or a portion of it as a stitch finger over which the stitches are formed is of 55 practical utility, yet it will be understood that we do not wish to be limited to any special type of machine.

An object of the invention is to provide an edge turner for an overseaming machine, 60 which edge turner is movable into and out of effective action on the fabric, while the machine is in operation.

A further object of the invention is to provide means for moving an edge turner, 65 as above stated, which means comprises devices for automatically moving the turner in one direction.

The invention also consists in the special arrangement of said turner, that is, between 70 the trimmer and needle; in the special manner of moving said turner, that is, diagonally out from the line of the seam; in its combined use as a stitch-finger as well as an edge turner; and in various other matters 75 all as hereinafter described and referred to in the appended claims.

The invention is illustrated in the accompanying drawings, in which:

Figure 1 is a front view of a portion of 80 an overseaming machine of the type above referred to, embodying our invention; Fig. 2 is a view partly in section, taken through the machine parallel with the line of feed, being in effect a view of the cloth plate with 85 the operating parts of the present invention attached thereto, and showing the presser foot, needle, and parts above the cloth plate; Fig. 3 is a plan view of the cloth plate and throat plate; Figs. 4 and 5 are enlarged 90 details of the throat plate, with the edge turner in different position respectively; Figs. 6 and 6^a are views of the seams formed by the turner and stitch forming mechanism, when the former is in the respective positions shown in Figs. 4 and 5; Fig. 7 is a perspective view of the cloth plate with our invention applied thereto; Fig. 8 is a detached view of the parts of the turner; Fig. 9 is a detail of the attachment of the turner 100 shank to its operating lever; Fig. 10 is a plan view of a modified construction of turner showing it of sufficient length to act as a stitch finger; and Fig. 11 is a view

similar to Fig. 2, showing the normal position of the turner as in position close to the throat plate, and folding the material, while in the other figures the normal position is its ineffective position.

In these drawings, 1 represents the bed plate of a sewing machine of the type above referred to, having the removable cloth plate 2, the gooseneck 3, the swinging cover 4, the trimming mechanism 5, the needle lever 6, needle bar 7, presser foot 8, and thread carrying loopers 9 and 10 coöperating to make an overedge stitch of the well known type. The removable cloth plate 2 has secured to it by screws, the throat plate 11, formed with the usual openings for the passage of the feed dog 12, and provided with the needle opening, the cut-out portion for the passage of the looper, and the stitch finger or tongue 13, over which the looper 9 lays its thread.

Slidably attached to the inner face of the cloth plate by the slot and screw connection 14 and 15, is the bar 16 having the adjustable stop blocks 17 thereon, to limit the sliding movement of the bar 16 on the screws 15. This sliding bar 16 has at one end the curved arm 18, pivotally connected to the end of the arm 19 of a lever, the other arm 20 of which has a socket in which is secured by a set screw 23, the shank 21 of the edge turner 22. The slide bar 16 has on its lower edge a ball lug 24 fitting in a socket 25 on the upper end of the vertical arm 26 of a pivoted bell crank lever, the horizontal arm 27 of which has attached to it a chain 28 leading down to the usual spring-pressed foot treadle, not shown. A spring 29 attached to the arm 26 and the cloth plate, keeps the slide bar normally in the position shown in Fig. 1, and the edge turner operated thereby in the position shown in Figs. 1, 3, and 4, that is, in position where it will not turn the edges of the goods as shown in Fig. 6^a, but permit them to be sewed with the flat seam shown in Fig. 6. By pressure on the treadle, the slide bar is moved to the position shown in Fig. 7; the movement is imparted to the lever 19, 20; and the turner 22 swings into the line of the seam in a diagonal direction, to the position shown in Figs. 5 and 7, when the seam shown in Fig. 6^a will be formed.

The thread carried by the looper 9 is laid over the turner and slips off the same onto the stitch finger 13. In Fig. 10, the turner 22' is lengthened and narrowed to form a double thickness of the stitch finger with the stitch finger 13.

In Fig. 11 an arrangement the reverse of that shown in Figs. 1 and 7 is illustrated, that is, the normal position of the slide bar 16 is such that the turner is up against the throat plate and turns the edge of the fabric, the spring 29' being vertical and operating on the arm 27.

It will be seen that we have thus provided

an edge turner movable diagonally into and out of the line of the seam, with means for rendering it effective and ineffective, without interfering with the action of the stitch-forming mechanism; that it may act to a greater or less extent as a stitch finger supplemental to the stitch finger in the throat plate; that all its operating parts are below the work support, the turner itself simply swinging into a position extending over the top of the throat plate; and that when in effective position it lies between the trimmer and the needle and turns the edge of the material over onto the body of the material, within the limits of the overedge stitching mechanism.

In the use of the arrangement shown in Fig. 10, and by making the tongue extension of the edge turner of sufficient length, it will be noted that it will be possible to dispense with the tongue on the throat plate. It will also be noted in this connection, as well as in the construction of the edge turner shown in the other figures of the drawings, that the turner makes a housing or casing covering the throat plate tongue on both sides thereof, thereby protecting said throat plate tongue against being struck by the needle in its descent.

As shown in Figs. 4 and 5, the throat plate is provided with a projecting ledge 30, upon which the edge turner rests when thrown into operative position, thereby supporting the same.

Various modifications and changes may be made in the construction of the parts of this device, without departing from the spirit of our invention.

Having thus particularly described our invention, what we claim as new and desire to secure by Letters Patent, is:

1. A sewing machine including in combination, feeding mechanism, overedge stitch forming mechanism, of a folder for turning over the edge of the material on to the body thereof, said folder being disposed relative to the stitch forming mechanism whereby the stitches are laid over said folder and are fed off from the folder on to the folded edge of the material, and means for rendering said folder effective or ineffective.

2. A sewing machine including in combination, feeding mechanism, overedge stitch forming mechanism, a device for engaging the edge of the material and turning the same over on to the body of the material within the limits of the overedge stitch forming mechanism, said device being disposed adjacent the stitch forming mechanism, whereby said folded edge is inclosed by the stitch forming mechanism as it leaves the folder, and means under the control of the operator for moving said device into and out of effective operation.

3. A sewing machine including in com-

5 bination, feeding mechanism, overedge stitch forming mechanism, a device for engaging the edge of the material and turning the same over on to the body of the material within the limits of the overedge stitch forming mechanism, said device being disposed adjacent the stitch forming mechanism, whereby said folded edge is inclosed by the stitch forming mechanism as it leaves 10 the folder, and means under the control of the operator for moving said device diagonally into and out of the line of seam.

15 4. A sewing machine including in combination, feeding mechanism, overedge stitch forming mechanism, a device for engaging the edge of the material and turning the same over onto the body of the material within the limits of the overedge stitch forming mechanism, whereby said folded edge is 20 inclosed by the stitch forming mechanism, and means under the control of the operator for moving said device diagonally into and out of the line of seam, said device also 25 acting as a stitch finger over which the stitches are formed.

30 5. A sewing machine including in combination over edge stitch forming mechanism, a folder for turning over the edge of the material on to the body thereof, said folder being disposed relative to the stitch forming mechanism whereby the stitches are laid over said folder and are fed off from the folder on to the folded edge of the fabric, and means for moving said folder from effective to ineffective position, including 35 manually controlled means for moving the folder in one direction, and automatic means for moving the folder in the other direction.

40 6. A sewing machine including in combination, feeding mechanism, a throat plate, overedge stitch forming mechanism, a combined folder and stitch finger, said folder extending above the throat plate for engaging and folding the edge of the material 45 whereby said folded edge is covered by the overedge stitches, and means for rendering said folder and stitch finger effective or ineffective during the operation of the machine.

50 7. A sewing machine including in combination, feeding mechanism, a throat plate, overedge stitch forming mechanism, of a combined folder and stitch finger, said folder extending above the throat plate for engaging and folding the edge of the material, means for moving said folder and stitch finger into and out of the line of seam diagonally thereof, whereby said folded edge is covered by the overedge stitches, and 55 means for rendering said folder and stitch finger effective or ineffective during the operation of the machine.

60 8. A sewing machine including in combination, feeding mechanism, overseaming stitching mechanism, a folder for turning

over the edge of the material onto the body thereof, said folder being disposed relative to the stitching mechanism, whereby stitches are laid over the folder and are fed off of the same onto the folded edge of the material, and means for rendering the action of the folder effective or ineffective without stopping the stitching mechanism. 70

9. A sewing machine including in combination, feeding mechanism, overseaming stitching mechanism, a folder for turning over the edge of the material onto the body thereof, said folder being disposed relative to the stitching mechanism, whereby stitches are laid over the folder and are fed off of 80 the same onto the folded edge of the material, and means for moving the folder into and out of operative position relative to the stitching mechanism without stopping the stitching mechanism. 85

10. In a sewing machine and in combination, a device for turning the edge of the fabric during its passage to the stitch-forming device, said device being provided with means to protect the turned edge from contact with the thread during the period of time that the turning action of the fabric takes place, and means for moving said device into and out of operative position without stopping the machine. 90

11. In a sewing machine, a needle, a trimming device for the edge of the fabric, a device in rear of said trimmer and in advance of said needle, said device being formed with a recess in the side thereof adjacent said needle, which recess extends from front to rear of said device, and means to move said device into and out of engagement with the fabric. 95

12. In a sewing machine and in combination, a stitch-forming mechanism, a tongue and a device for forming the stitch over said tongue, a second tongue mounted in a plane above said first tongue, and means whereby one of said tongues can be thrown into and out of said operative position, said movement being toward the front of the machine whereby said tongue is withdrawn from beneath the stitches. 105

13. In a sewing machine and in combination, stitch-forming mechanism including a plurality of tongues over which the stitch is laid during the formation of the seam, means located upon the opposite sides of said tongues to deposit a thread over the same, and means whereby one of said tongues can be withdrawn from said seam at the will of the operator and while the machine is in operation. 115

14. In a sewing machine and in combination, stitch-forming mechanism including a plurality of tongues over which the stitch is laid during the formation of the seam, means for forming the stitch over said tongues, and means whereby one of said tongues can 120 130

be withdrawn from said seam at the will of the operator and while the machine is in operation.

15. In a sewing machine, in combination, 5 a device for forming an initial fold upon the edge of the fabric, stitch-forming mechanism including means for laying a thread over the edge of the initial folded fabric as it leaves the folding device to complete 10 the folding action upon the fabric, and

means whereby said folding device may be rendered effective or ineffective.

In testimony whereof we affix our signatures, in presence of two witnesses:

JAMES R. MOTTATT.
